UNITED STATES PATENT OFFICE

CHARLES LIONEL MARCUS, OF NEW YORK, N. Y.

DESIGN FOR A BOTTLE RACK OR SIMILAR ARTICLE

Application filed July 12, 1930. Serial No. 36,339. Term of patent 14 years.

To all whom it may concern:

Be it known that CHARLES LIONEL MARCUS, a citizen of the United States and resident of New York city, in the county of New York and State of New York, has invented a new, original, and ornamental Design for a Bottle Rack or Similar Article, of which the following is a specification, reference being had to the accompanying drawing, forming part thereof, in which,

Figure 1 is a perspective view of a bottle rack embodying my new design.

Fig. 2 is a top plan view of the device shown in Fig. 1.

I claim:

The ornamental design for a bottle rack or similar article, substantially as shown.

Dated, New York city, June 28th, 1930.

CHARLES LIONEL MARCUS.
